ATTORNEY

UNITED STATES PATENT OFFICE.

SPENCER BICKERTON, OF HONOLULU, TERRITORY OF HAWAII.

STAMP-BOOK HOLDER.

1,257,789.

Specification of Letters Patent. Patented Feb. 26, 1918.

Application filed June 5, 1917. Serial No. 173,014.

To all whom it may concern:

Be it known that I, SPENCER BICKERTON, a citizen of the United States, residing at Honolulu, Territory of Hawaii, have invented new and useful Improvements in Stamp-Book Holders, of which the following is a specification.

This invention relates to holders or protectors for books, and is primarily intended for the reception of stamp books of the kind issued by the Post Office Department.

The object of the invention is to provide a holder or protector for stamp books and the like which is neat and attractive in appearance, of simple construction and of a convenient size to be carried in the pocket.

A further object of the invention is the provision of a device of this class in which the stamp book may be removably secured therein in a quick and easy manner and when so secured will remain in position until intentionally removed.

With the above and other objects in view the invention consists of the combination and arrangement of parts hereinafter more fully described, illustrated in the accompanying drawings and pointed out in the claim hereto appended.

In the drawings:

Fig. 1 is a perspective view of a stamp book holder or protector constructed in accordance with the invention, a book being shown in position therein;

Fig. 2 is a longitudinal sectional view of the same; and

Fig. 3 is a detail horizontal sectional view through the pocket end of the holder, with the book therein, the end of the pocket being swung open to permit the removal of the book.

Like characters of reference denote corresponding parts throughout the several views of the drawings.

In carrying out the invention, the same includes a base 10 which is formed of thin metal and may be made of aluminum, silver or any other suitable material. The area of this base is slightly greater than the side

of the stamp book, and is formed at one end with a pocket 11. This pocket comprises a rear portion 12, a permanent closed end 13, a hinged end 14, a top 15 and a bottom 16, the latter being a continuation of the base 10. Projecting inwardly from the permanently closed end 13 is a retaining pin 17, provided with a sharpened point so that it may easily enter between the leaves of the stamp book, which is shown at A to aid in holding the book in position. The hinged end 14 is hinged as at 18 and carries a pin 19, the location of which is opposite the pin 17 to coöperate therewith to securely hold the book in position. In order to further protect the book there is provided a top 20 which is hinged to the upper longitudinal edge of the pocket by means of a spring hinge 21, which normally holds it in contact with the cover of the book.

In order to insert the book within the holder, the hinged end 14 is opened and the top 20 lifted, and the book inserted upon the pin 17. When the end 14 is closed the pin 19 engages the book at the side opposite the pin 17.

It will be seen from the foregoing that the invention provides a neat, attractive and convenient holder and protector for stamp books which is constructed in such a manner as to permit ready access to the book for the purpose of removing the stamps therefrom.

Having described the invention, what is claimed is:

A device of the character described comprising a base, a hinged cover therefor, a pocket formed at one end of said base, one end and back of said pocket being permanently closed, an inwardly projecting pin carried by the closed end, a hinged end located opposite the closed end and a pin carried by said hinged end and coöperating with the first mentioned pin for removably securing a book within the pocket.

In testimony whereof I affix my signature.

SPENCER BICKERTON.
